United States Patent

Des. 237,803
Patented Nov. 25, 1975

237,803

TELEPHONE DIAL BUTTON

Gerhart F. Klaiber, Deal, and Donald Foggia, Oakhurst, N.J., assignors to TIE/Communications, Inc., Stamford, Conn.

Filed June 3, 1974, Ser. No. 475,853

Term of patent 14 years

Int. Cl. D14—03

U.S. Cl. D26—14 A

FIG. 1 is a perspective view of a telephone dial button showing the new design.

FIG. 2 is a plan view of the top of the button of FIG. 1.

FIG. 3 is an elevation view of the button of FIG. 1 as viewed in the direction of the arrow 3 in FIG. 2.

FIG. 4 is an elevation view of the button of FIG. 1 as viewed in the direction of the arrow 4 in FIG. 2.

FIG. 5 is an elevation view of the button of FIG. 1 as viewed in the direction of the arrow 5 in FIG. 2.

FIG. 6 is an elevation view of the button of FIG. 1 as viewed in the direction of the arrow 6 in FIG. 2.

FIG. 7 is a plan view of the bottom of the button of FIG. 1.

We claim:

The ornamental design for a telephone dial button, as shown and described.
